UNITED STATES PATENT OFFICE.

GEORGE L. CAMPBELL, OF NYACK, NEW YORK, ASSIGNOR TO INTERNATIONAL ELECTRIC TRACTION COMPANY, A CORPORATION OF WEST VIRGINIA.

ELECTRIC-RAILWAY SYSTEM.

SPECIFICATION forming part of Letters Patent No. 699,787, dated May 13, 1902.

Application filed August 23, 1901. Serial No. 73,083. (No model.)

To all whom it may concern:

Be it known that I, GEORGE L. CAMPBELL, a citizen of the United States, residing at Nyack, in the county of Rockland and State of New York, have invented a certain new and useful Improvement in Electric-Railway Systems, of which the following is a specification, reference being had to the accompanying drawings, which form a part of the same, the same 10 reference characters referring to similar parts in the various figures.

This invention relates to electric-railway systems such as are shown and described in Letters Patent of the United States No. 15 656,511, granted to me August 21, 1900, and No. 621,321, granted to me on March 21, 1899. In these systems a closed conduit is employed having a continuous and a discontinuous conductor in said conduit, the sections of said 20 discontinuous conductor being connected to a sectional contact-rail. A trolley is moved along said conduit under the influence of a car-magnet to charge said sectional contact-rail. This invention relates more particularly to crossings and switches for such 25 systems.

Figure 1 is a plan view showing my invention. Fig. 2 is a perspective view showing a detail of the same. Fig. 3 is a detail sectional 30 view.

A represents track-rails which communicate by means of suitable switch mechanism (not shown in detail, but of ordinary and well-known construction) with track-rails B. The 35 track-rails D intersect substantially at right angles the track-rails A to form a crossing.

The closed conduits G, G', and G² are constructed below the surface of the street substantially in the center of the track-rails A, 40 B, and D. These conduits communicate with each other, since they are all upon substantially the same level, and the conduits G and G' are formed at their point of intersection with a slightly-relieved curved portion, as indicated in Fig. 1, so that trolleys can pass 45 from one of these conduits to the other under the guidance of suitable car-magnets. The discontinuous contact-rails E, E', and E² are also between the track-rails to supply current 50 to cars operating upon the same. These con-

tact-rails, as are indicated in Fig. 1, are to one side of the closed conduits which supply them with current, and since it is preferable to form these contact-rails of iron they should be removed a sufficient distance from such 55 conduits, so that they do not interfere with the magnetic control of the car-magnets over said conduits. As is well known in this art and as is described in detail in my Patent No. 656,511, each of these conduits is formed 60 of insulating non-magnetic material G, as indicated in Fig. 3, and the continuous conductor J, secured to the bottom of the conduit, as is indicated in that figure, supplies current through the traveling closer or trolley K 65 to the sectional conductor L, mounted on the top of the conduit. The sections of this sectional conductor are connected with the sectional contact-rails, the two sections E' and E² being indicated in Fig. 3. The car-magnet M, 70 mounted in any suitable way on a car, moves along directly over the closed conduit, and the magnet, which is energized by current supplied to it in any suitable way, acts upon the iron armature carried by the trolley K and 75 draws this trolley along the conduit directly under the car-magnet. The sectional contact-rail, as is indicated in Figs. 1 and 3, does not extend up to the intersecting track-sections in any case; but the insulating-blocks are 80 inserted to insulate the contact-rails from the two sections. These insulating-blocks, together with the contact-rail, are elevated above the level of the intersecting track-sections at the crossing, as is shown in Fig. 3. 85 The elongated contact-shoe N, mounted on the car in any desired way, makes contact with the sections of the contact-rail, and at a crossing, as indicated in Fig. 3, the contact-shoe is of sufficient length so that it does not 90 come into contact with the track-rails at any time, and, furthermore, the contact-shoe is always in contact with one section of the contact-rail, so that current is at all times supplied to the car. It is of course understood 95 that contact-shoes of various kinds may be employed and special forms of contact devices may be used instead of a simple shoe here indicated.

As is shown in Fig. 1, the track-rails C also 100

intersect the track-rails A and B. These track-rails, however, are not intended for the same electric system which it is intended to operate on the other tracks. These track-
 5 rails have no conduit or sectional contact-rails. It is of course desirable to make these track-rails wherever possible of ordinary steel for the sake of cheapness and durability. It is undesirable, however, to form the section
 10 of track-rail which extends over the conduit employed in my electric-railway system of ordinary steel, since this would interfere with the magnetic control of the car-magnet over the traveling closer or trolley. The section
 15 F³, therefore, of the track C is formed of suitable non-magnetic material, and I prefer to form this section as a casting of manganese steel, the composition of this steel being such that it is practically non-magnetic and does
 20 not interfere to any appreciable extent with the magnetic control of the car-magnet over the trolley. As is shown in Fig. 1, the frog F where the tracks C and A intersect is substantially over the closed conduit G', and for
 25 similar reasons this frog, at least where the tracks pass over the closed conduits, must be formed of similar non-magnetic material. I show in Fig. 2 the details of construction of this frog, which may be formed by casting it
 30 in one piece or in any other desired way. The housings H' and H² are formed, preferably, integral with the adjacent track-sections F' and F² to surround the conduits G and G'. The bolt-holes h are formed in the housings
 35 for the more convenient securing of the conduits to the housings. In this way, as will be readily seen, the rail-section is sufficiently supported by the housings, so that the conduit passes through the rail. The strength
 40 of the rail at this point is not materially lessened. As is seen in Fig. 3, the housings, which extend on either side of the rail to some little distance, are covered by the paving material, such as asphalt, and since these housings and
 45 the rail-section over the conduits and adjacent thereto are non-magnetic so that the car-magnet M has the same perfect control over the trolley at this point that it has at all other points in the conduit. The track-rails
 50 are supported in any desired way, and the contact-rails are supported in any usual manner, so as to insulate them properly and prevent leakage. These contact-rails are preferably elevated throughout their whole ex-
 55 tent above the level of the track-rails, as indicated in Fig. 3, and suitable depressions are made in these contact-rails, so that the car-magnets do not come in contact with them and pass without touching. Such a depressed
 60 portion is indicated at H', for instance, in Fig. 1. These depressed portions occur, of course, wherever the contact-rails pass over the conduit, or, if desired, the car-magnet M may be raised by suitable mechanism, such
 65 as by a non-conducting wedge-shaped shoe at the other end of the magnet, covering the poles of the same above the contact-rails, so

that the car-magnet will by these means be held out of contact with the contact-rails in passing over them, or, if desired, the car-magnet may be mounted at a sufficient height 70 to be above the contact-rails at all times. It is of course apparent that instead of having the closed conduits passing through the web of the rail, as indicated in Figs. 2 and 3, these 75 conduits might pass entirely under the rails, in which case of course the rails would necessarily be made non-magnetic for the reasons already set forth. The track-section F⁴ is made of similar non-magnetic material, as 80 are also the track-sections F⁵, F⁶, F⁹, and F¹⁰. Furthermore, it is necessary to construct the sections of the contact-rails where these rails pass over the closed conduits of similar non-magnetic material to prevent any interference 85 with the proper magnetic control of the car-magnet over the trolley in the conduit. The sections E³, F⁷, and F⁸ of these contact-rails are therefore made of non-magnetic material, preferably of manganese steel. These 90 sections must be necessarily constructed of suitable conducting material, so as to properly supply the electricity to the contact-shoe carried by the car.

I prefer to form the sections E⁴ and E⁵ of 95 the contact-rails so that these sections are electrically connected with the sections F⁷ and F⁸, and this central part of the contact-rails is charged whenever a car passes over the crossing in either direction, although these 100 sections of contact-rail on different tracks may, if desired, be insulated.

Many modifications may be made from the disclosure which I have made in this case. The track-sections over the conduit may be 105 formed of any non-magnetic material—such as brass, bronze, or even hard wood, if desired. Many changes may also be made in the exact form of these rail-sections without departing from the spirit of this invention. 110 I do not, therefore, wish to be limited by the disclosure which I have made in this case; but

What I desire to secure by Letters Patent is set forth in the appended claims: 115

1. In an electric-railway system track-rails, intersecting track-rails to form a crossing, a closed conduit extending adjacent said track-rails, a continuous and a sectional conductor in said conduit, a sectional contact-rail adjacent said conduit connected to said sectional conductor, the sections of said contact-rail being above the level of said intersecting track-rails at said crossing and insulated therefrom, a trolley in said conduit to connect 120 said conductors, a car-magnet mounted on a car to control said trolley, an elongated contact-shoe mounted on said car to make contact with said contact-rail, the intersecting track-sections above said conduit being 125 formed of manganese steel to provide a non-magnetic housing for said conduit.

2. In an electric-railway system embodying track-rails, and a closed conduit, intersecting

- track-rails forming a crossing, a sectional contact-rail electrically energized from said conduit by magnetic means, said contact-rail being higher than said intersecting track-rails 5 at said crossing, the intersecting track-rails over said conduit being non-magnetic so as to be free from interference with said conduit.
3. In an electric-railway system embodying a sectional contact-rail, a closed conduit and 10 magnetically-actuated means in said conduit to charge said contact-rail, and a non-magnetic track-section.
4. In an electric-railway system embodying a sectional contact-rail, a closed conduit and 15 magnetically-actuated means in said conduit to charge said contact-rail, a manganese-steel track-section forming a non-magnetic housing for said conduit.
5. In an electric-railway system, track-rails, 20 a magnetically-operated closed conduit and sectional contact-rails intersecting at a crossing, there being a section of said sectional contact-rails within the track-rails at said crossing, said contact-rails being elevated 25 above said track-rails.
6. In an electric-railway system, track-rails, a magnetically-operated closed conduit and a sectional contact-rail parallel to said track-rails, intersecting track-rails to form a crossing, 30 there being an insulated section of said sectional contact-rail between said intersecting track-rails, insulating-blocks to insulate said sectional contact-rail from said intersecting track-rails, said sectional contact-rails 35 and said insulating-blocks being elevated above said track-rails.
7. In an electric-railway system, track-rails,
- an intersecting sectional contact-rail elevated above said track-rails at its intersection with the same and elevated insulating-blocks between said contact-rail and said track-rails. 40
8. In an electric-railway system track-rails, magnetically-operated closed conduits and sectional contact-rails intersecting at a crossing, said contact-rails being elevated above 45 said track-rails at said crossing and being formed with depressed non-magnetic portions where they pass over said conduits.
9. In an electric-railway system track-rails, closed conduits and sectional contact-rails intersecting at a crossing, said contact-rails being elevated above said track-rails at said crossing and being formed with non-magnetic sections above said conduits, a contact-shoe, a car-magnet and means to maintain said car- 50 magnet out of contact with said contact-rails.
10. In an electric-railway system, track-rails, a magnetically-operated closed conduit parallel to said track-rails, intersecting track-rails to form a crossing said intersecting track-rails being formed with non-magnetic sections 55 over said conduit.
11. In an electric-railway system, track-rails, magnetically-operated closed conduits parallel to said track-rails and sectional contact-rails of magnetic material parallel to and removed from said conduits intersecting at a crossing, there being non-magnetic sections of said sectional contact-rails over the intersecting conduits. 60
